UNITED STATES PATENT OFFICE.

CLEMENT RESTEIN, OF PHILADELPHIA, PENNSYLVANIA.

PACKING.

No. 843,630.

Specification of Letters Patent.

Patented Feb. 12, 1907.

Application filed September 21, 1905. Serial No. 279,384.

To all whom it may concern:

Be it known that I, CLEMENT RESTEIN, a citizen of the United States, and a resident of Philadelphia, in the county of Philadelphia and State of Pennsylvania, have invented 5 certain new and useful Improvements in Packing, of which the following is a specification.

The principal object of the present invention is to provide a packing for use especially in connection with high steam-pressures—such, for example, as those to which locomotive throttle-valves are subjected—and which packing shall be efficient, reliable, 15 durable, and comparatively inexpensive.

The invention comprises the improvements to be presently described and finally claimed, and the nature, characteristic features, and scope of the invention will be more 20 fully understood from the following description, taken in connection with the accompanying drawings, forming part hereof, and in which—

Figure 1 is a perspective view of a packing 25 embodying features of the invention. Fig. 2 is a sectional view illustrating the same in application to a gland or stuffing-box, and Fig. 3 illustrates conventionally in plan and section some of the material which enters into 30 the construction of the packing.

In the drawings, 1 and 2 are wedge-shaped sections consisting, respectively, of a roll of wired asbestos cloth cemented and pressed into wedge form. The wired asbestos cloth 35 is shown in Fig. 3, in which 3 represents the asbestos strands, and 4 the wire-strands; but of course the strands may be differently arranged. The various layers of the rolled cloth may be cemented together, as by means 40 of so-called "rubber-cement," and the rolled sheet, which would normally be of cylindrical

form, is consolidated and pressed into wedge form by any suitable means.

5 is a rubber cushion, and its purpose is to afford the wedge-sections freedom of sliding 45 motion in response to the requirements to which they are subjected.

6 is an envelop or wrapper of asbestos cloth or material either with or without wire, and it surrounds the wedges and the rubber 50 cushion.

The packing may be lubricated, for example, with graphite. Externally the packing is generally of rectangular form, but is five-sided, so that one of its corners is beveled, as 55 at 7. This accommodates the packing to the wall of the stuffing-box.

It will be obvious to those skilled in the art to which the invention relates that modifications may be made in details without departing from the spirit thereof. Hence the invention is not limited further than the prior state of the art may require; but,

Having thus described the nature and objects of my invention, what I claim as new, 65 and desire to secure by Letters Patent, is—

1. A packing comprising a wrapper or envelop, a rubber cushion and two wedge-shaped sections each consisting of a consolidated roll of wired asbestos cloth, substantially as described.

2. A packing comprising an asbestos wrapper or envelop, a rubber cushion and two wedge-shaped sections each consisting of a consolidated roll of wired asbestos cloth, substantially as described.

In testimony whereof I have hereunto signed my name.

CLEMENT RESTEIN.

In presence of—

W. J. JACKSON,
K. M. GITTIGAN.
